UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING-PLATE.

No. 902,281.

Specification of Letters Patent.

Patented Oct. 27, 1908.

Application filed April 22, 1908. Serial No. 428,504.

To all whom it may concern:

Be it known that I, JOSEPH S. DUNCAN, a citizen of the United States, residing at Chicago, in the county of Cook and State of Illinois, have invented new and useful Improvements in Printing-Plates, of which the following is a specification.

My present invention relates to that class of printing devices which are usually arranged in accordance with a card index system and are fed through a printing machine and packed one at a time, after the printing operation, in the tray or drawer in which they are stored. These printing devices usually bear an address form but they may be provided with any other form desired.

My Letters Patent No. 764,660 dated July 12, 1904 and No. 803,677 dated Nov. 7, 1905 cover machines for handling printing devices in this manner. It sometimes happens, through carelessness or otherwise, that the printing device is discharged from the printing machine into the tray or drawer improperly so that, instead of standing upright on one edge, it will fall down into a position which will interfere with the proper packing and nesting of the other printing devices.

The object of this invention is to provide a printing device with means for engaging the tray or drawer so that it will be sustained in proper position in the drawer for packing.

In the accompanying drawings Figure 1 shows a portion of an index printing device embodying the invention. Fig. 2 shows an entire index printing device embodying the invention. Fig. 3 is an end view of the printing device shown in Fig. 2. Fig. 4 shows another index printing device embodying the invention. Fig. 5 is an end view of the printing device shown in Fig. 4. Fig. 6 shows a portion of a plain printing device embodying the invention. Fig. 7 shows a portion of the blank from which the printing device shown in Fig. 4 is made.

The printing device preferably consists of a plate 8 stamped from a single sheet of metal with spacing flanges 9 along its side edges on the back of the plate, as shown in Figs. 1-3, or on the face of the plate, as

shown in Figs. 4 and 5. The printing characters are preferably stamped in relief on the plate and run in lines lengthwise thereof. One end of the plate may be provided with a recess 10, as shown in Fig. 6, or with a recess 11 and an index tab 12, as shown in Figs. 1, 5 and 4.

The blank 13 (Fig. 7) from which the plate is made is cut to form projections 14, preferably in the form of hooks as shown, and when the side edges of the plate are bent over to form the spacing flanges 9 these projections are bent outward to extend beyond the side edges of the plate. The projections are preferably located above the middle of the plate and they are constructed and arranged in a suitable manner to engage guides at the sides of the tray or drawer in which the plates are packed and stored so that by reason of such engagement the plates will always be sustained in proper position for packing or nesting one upon or against the other. By thus forming the projections out of the blank for the plate and within the margin thereof I avoid waste of material, and no increase in the size of the blank is required.

When the printing devices are discharged from the printing machine they will drop, one at a time and one in front of the other, in the tray or drawer which is suitably arranged to receive them, and the projections will engage guides in or on the tray or drawer or otherwise suitably arranged to prevent the plates from falling flatwise in the tray or drawer and to sustain them in proper position for packing or nesting snugly.

What I claim and desire to secure by Letters Patent is:

1. A printing device consisting of a substantially rectangular metal plate having printing characters thereon, and oppositely disposed projections stamped out of the blank for the device, within the margin thereof, and bent outward to project beyond opposite edges of the plate.

2. A printing device consisting of a metal plate having printing characters thereon, spacing flanges formed by bending over the side edges of the plate, and hook projections

stamped out of the blank for the plate, within the margin thereof, and bent outward.

3. A printing device consisting of a metal plate of substantially rectangular form and
5 having printing characters thereon, and hook
projections stamped out of the blank for the
device, within the margin thereof, and bent

outward to project beyond the side edges of the plate and extending substantially parallel with said side edges.

JOSEPH S. DUNCAN.
